INTERNAL COMBUSTION ENGINE
CYLINDER HEAD

Irving E. Aske, Muskegon Heights, Mich.

Application May 15, 1941, Serial No. 393,557

5 Claims. (Cl. 123—191)

My present invention relates to improvements in internal combustion engine cylinder heads, and particularly to the combustion chambers thereof and similar in class to combustion chambers as described in my United States Letters Patent, No. 2,138,131, issued November 29, 1938, and the objects of improvement are: first, to provide an internal combustion engine cylinder head having a combustion chamber that will improve the distribution of the combustible fuel mixture; second, to increase the horsepower output of the engine; third, to decrease the fuel consumption; fourth, to minimize engine roughness or shock; and fifth, to reduce the mechanical shock on the pistons and bearings, thereby increasing the wear life of the engine.

I attain the aforesaid objects and others that will be apparent from a perusal of the description when taken in connection with the accompanying drawings, in which:

Figure 1 is a sectional view of my cylinder head taken on a line I—I of Figure 2, hereinafter described.

Figure 2 is an under or cylinder closing face plan view of the cylinder head illustrating my preferred arrangement of the combustion chamber and parts pertaining thereto.

Figure 3 is a chart showing in the upper portion, by curves, the percentage of total volume for any given percentage of the total distance from the point of ignition, and in the lower portion their respective curves that show the ratios of the percentage volumes removed to the corresponding percentage radial distances. The total volume represents the total compressed volume in the combustion chamber, and the total distance is the maximum spherical radius distance taken from the point of ignition to the outer boundary wall 7 as shown in Figure 2 of the combustion chamber portion over the cylinder bore.

Throughout the several views comprising the drawings, similar numerals refer to similar parts and referring thereto:

Numeral 1 represents the cylinder head body portion having formed therein a cooling fluid chamber 2, a cylinder closing face 3, in which is depressed combustion chamber 4 having a long extended portion 5 and a shorter extended portion 6, joined over the cylinder bore 7 designated by broken line 8 by curved wall 10, the portion 11 of the combustion chamber boundary wall extends in an irregular curve 12 from its juncture with the wall of the long extension 5 to around the spark plug position 13, and joins the curve wall 14 extending around the exhaust valve 55

chamber portion 15 to the short extended portion 6. Spark plug 16, by suitable electric current, provides the electric jump spark for igniting the fuel charge compressed within the combustion chamber, and having opening into said chamber products of combustion exhaust valve 16'.

Numerical 17 illustrates the upper portion of a cylinder block of the engine closed by cylinder head body 1, except for the opening 18 between the combustion chamber 4 and the cylinder bore 7. A sealing gasket 19 is placed between the head body 1 and the cylinder block 17. Suitable bolts passing through holes 20 attach the cylinder head body securely to the cylinder block, and holes 21 provide for circulation of cooling fluid between the cylinder block and head, and 22 represents the position of the point of ignition.

Referring to Figure 3 which represents the bogey OABCDEFG established from an analysis of the combustion volume distribution of combustion chambers used in most present engines. From measurements taken of vibration noise and the relative harshness of internal combustion engine's operation having various arrangements of volume distribution, it became possible to erect a chart of my improved combustion chamber performance bogey, which extends beyond the bogey OAFG, Patent No. 2,138,131, by the area ABCDEFA. In my experiments it was discovered that when the ignition took place in a larger volume of fuel surrounding it, giving the ordinate HP, the power was greater than when the volume was smaller, having the ordinate HK. Near the end of complete combustion, representing about 72% of the length of the combustion chamber, it was found advantageous to have a larger volume of fuel to burn, which is shown by ordinate MN than the smaller volume MR. By carefully proportioning the initial end and the end volumes of the chamber so as to produce peaks well within the area ABCDEFA, more power and better economy results than when they are reduced to come within the bogey OABC of my said Patent No. 2,138,131.

From further study, it was found that when the maximum incremental volume to incremental distance ratio took place within 40% of the maximum radius distance S from ignition point 22 of Figure 3, there was a substantial improvement over a chamber having the same maximum value occurring at a greater distance from the ignition point. Graphs LPNJ and TWZ serve to illustrate the differences in combustion chamber

characteristics between a smooth and rough running engine.

Each of the aforesaid combustion chambers having the same volume, but differ in their respective maximum radius distances, position of the ignition point, and volumetric arrangement considered from said ignition point, therefore any chamber graphically analyzed for volume distribution that has maximum values coming within the area ABCDEFA will be most satisfactory for engine operation smoothness and high economy. A high peak in the graph during the first 40% of distance is an advantage over a lower value, so long as the limits of the bogey are not exceeded.

In constructing the graphs of Figure 3, I first lay out the ordinate and abscissa to convenient scales. The abscissa representing the percentage of radius distance taken from the point of ignition to the outermost edge of the combustion chamber. The distance S, Figure 2, is taken as one-hundred percent, and it should be noted that this distance does not take in the entire clearance distance over the top of the piston, but is limited to the farthest extremity of the combustion chamber from the point of ignition.

The ordinate referred to is laid out from zero to two-hundred and represents the ratios of incremental volumes to the corresponding incremental distances multiplied by one-hundred, and is based upon one-hundred percent volume and one-hundred percent distance.

From the respective ratios obtained by analyzing two different combustion chambers for volume distribution by my method, herein described, the graphs LPJ and TWZ were constructed.

The percent of total volume for each volume increment V divided by the corresponding percent of total radius distance increment S, multiplied by one-hundred, establishes the respective points of the graphs LPJ and TWZ.

The graphs L'J' and T'Z' represents the percentage of volume V contained in the chamber for any given percentage distance S of the chamber taken from the point of ignition. As an example, at 40% distance the chamber contains 34% of the total volume for graph L'J'. For graph T'Z' the percent volume is 17.

The graph LPJ also indicates the space rate of change of incremental volumes consumed at constant pressure, as the inflammation wave spreads through to the outermost limits of the chamber as shown in the lower part of Figure 3. The ordinate HP taken at the point of maximum value, representing 40% of the total radial distance of the chamber, corresponds to the ratio 183. This value indicates that the volume at that point is increasing 1.83 times as fast as the lineal radial distance for the same interval S, which represents about 3 1/2% of the total radius distance.

The distance from the ignition point 22, to the outermost limit or boundary of the chamber is designated by line S in Figure 2, and fixed at 100% of the spherical radius distance in the chart of Figure 3. The increment S of the graphs corresponds to the interval S of Figures 1 and 2, where S represents a lineal radial distance or increment swept through by the flame as it travels forward on the spherical radius S. During the distance S a volume V is consumed. Symbol V represents 100% of total volume of the chamber, gasket clearance, and piston clearance when the piston is at the top of its stroke of compression.

The area enclosed by the boundary lines passing through the points ABCDEFA, is my bogey within which the maximum incremental volume to distance ratios will substantially occur for all combustion chambers coming within the scope of my invention. The abscissas and ordinates of points ABCDEFA are designated respectively by the figures (22%, 148), (30%, 200), (40%, 200), (50%, 140), (80%, 160), (87%, 120).

10 The shape and amplitude of the curve LPNJ depends upon the position of the ignition point relative to the distribution of volume of the combustion chamber. As there are a large number of locations for an ignition point in any combustion chamber of given shape and volume, there will be found only a few locations which will substantially satisfy the conditions imposed by my bogey, and give satisfactorily smooth operation of the engine.

20 To facilitate the work of analyzing a combustion chamber for volume distribution, I employ a plaster of Paris cast made of the shape of the entire interior of the combustion chamber, including the gasket and piston clearance volume. The ignition point is carefully located on the cast, and the cast is mounted upon a turntable machine designed for the purpose of sweeping out or removing definite spherical portions of the plaster, preferably one-eighth inch in width at given radial distances from the ignition point to simulate the shape of the combustion wave front. The spherical shaped portions thus removed, which come out in the form of powder, closely represent the progress of the flame wave front as it travels through the chamber. The weight of these powdered portions represent relatively exact volume proportions of the fuel mixture that are burned when compared to the total weight of the cast. These incremental portions are expressed in percent of the total weight of the cast, and the incremental distance as the percent of the maximum radius distance. Thus it is quite simple to cut up the cast into a large number of small increments and construct the graphs L'J', T'Z' and their corresponding graphs LPNJ, TWZ.

25 To further illustrate the progress of the combustion wave front through the combustion chamber volume, refer to Figure 3. Combustion starts at the ignition spark, between the terminals of the spark plug, preferably located in the deepest portion of the combustion chamber above the valve area, and it spreads in a supposedly concentrically spherical wave front consuming combustibles in proportion to the volumes swept through from the ignition spark to the curved wall 10, and into the farthest extended portions 5 and 6 of the combustion chamber, then through the passage 18 into the clearance space 18' between the piston and face 3 of the cover. The area of the passage 18 is considerably greater than the area of the fuel inlet valve opening which is not shown but is a counterpart to the exhaust valve 18' which is substantially closed at the start of ignition and throughout duration of combustion. When the combustion wave reaches the extended portion 5, the outermost boundary point of the chamber, all combustibles of the fuel will have been consumed in its path, in proportion to the incremental volumes encountered. Thus, the progression of the combustion wave front can be made to generate pressures at predetermined values, so as to increase uniformly to the total force applied to the piston and not with the sudden, blow-like impulse of highly accelerated

pressures, as of many conventional combustion chambers where combustible volumes are improperly or haphazardly arranged in relation to the progress of the wave front from the point of ignition.

Referring to the subject matter of my Patent No. 2,138,131, issued November 29, 1938, the ignition point was so located with respect to the combustion volume so as to greatly limit the amount of fuel burned during the early stage of combustion. The effect of that limitation was to unduly retard the generation of pressure. In my present invention, the ignition point is so located in relation to the combustible volume that a much larger portion of the volume is burned during the early stage of combustion, the effect of the increase in initial combustion, combined with a smaller increase near the later end, is to improve engine smoothness of operation, increase its power output, and lessen the tendency of the engine to detonate under low octane rated fuel.

In carrying out my present invention and to obtain these named objects, it is necessary to set forth certain geometrical relations applying to the shape and volume of the engine's combustion chamber, and location of the spark plug whereby one skilled in the art can accurately design a combustion chamber to more closely approach the ideal form without having to resort to the usual cut and try methods at present employed, which involve great expense by necessarily having to conduct many operative tests on an engine and which, in most cases, form no base for comparisons from which accurate conclusions can be drawn for establishing a working standard in designing combustion chambers. In my present invention it is only necessary to apply the fundamental facts concerning combustion of the fuel that have been established by scientific investigation, to wit: that the ignition spark ignites only that portion of the fuel mixture in which it is closely surrounded, that the initial ignition ignites succeeding zones of radially adjacent fuel, and thereby produces a flame wave that spreads from the point of ignition throughout the fuel mixture until all combustibles therein are ignited and burned; that the velocity of the combustion process is substantially rapid in all directions from the point of ignition, and consequently forms a spherical wave front emanating from said point; that the volume contained in the wave front equals that of the incremental portions of fuel mixture it encounters at its respective distance from the point of ignition, and that the volume of the incremental portions consumed at the wave front are determined by the volume and shape of the combustion chamber as related to the point of ignition; that the pressures developed at any stage of the combustion flame front are closely proportional to the ratio of the incremental fuel mass consumed at the wave front to that of the entire mass of fuel to be burned when the piston is at the starting of the power stroke. Hence, pre-determination of the rate of pressure rise due to combustion can be empirically predicted and closely controlled through proper volume distribution in the combustion chamber as related to the point of ignition.

It is generally understood that when small volumes of fuel are ignited and begin to burn, pressure is generated which rapidly increases as the burning process continues and the rapidity of this increase in pressure attainment sets up reaction or rebound forces against the unburned

fuel portion, the piston head, connecting rod, crankshaft and bearings, which all act as sudden and blow-like impulses that give rise to mechanical vibration and engine roughness in addition to inducing detonation in the unburned fuel portion of the combustion spaces, and the greater the volume of the fuel burned at any instant at the flamed front, the greater and more rapid will become the pressure increase and the greater will be the magnitude of the applied and restoring forces.

The magnitude of pressure change in pounds per square inch per second provides a comparative measure for judging the vibration roughness of the engine's operation, as its effects in producing vibration are far more pronounced than the maximum pressure developed in pounds per square inch from the entire explosion-like combustion to the fuel. For illustration, if a pressure of one-hundred pounds per square inch uniformly increases to one-hundred and fifty pounds per square inch in one thousandth of a second, the rate of change of pressure would be fifty thousand pounds per square inch per second. Therefore the accelerating force necessary to establish the above rate of change of pressure would be fifty million pounds per square inch per second per second, since the acceleration is the rate of the velocity change for a unit of time. If the growth of this pressure was limited to one-half the former amount, by restricting the consumption of fuel to one-half its former amount, the rate of change of pressure and accelerating force would be reduced by one-half of their former values. When the rate of pressure change and acceleration forces are multiplied by the piston area they become very large, and create rough and noisy operation and possible damage to the engine parts.

It should be understood that it is not only necessary to limit the rate of change of pressure to low values, but to properly position the occurrence in the combustion cycle, as what might be thought a low value of combustible volume during the early stage of combustion could become a high value at a later stage of combustion, because of the initial expansion and temperature of the burned fuel greatly increasing the density, and temperature of the fuel volume in advance of the flame front that is about to burn.

It is obvious in the light of these factors that the arrangement of combustible volume distribution, considered from the point of ignition, must be carefully chosen in designing a combustion chamber for minimizing of engine operation roughness, as distinguished from combustible values that are almost universally arranged as in the general design of present combustion chambers.

In the past and at present, designs of combustion chambers reflected the skill of the designer, his judgment and ability to provide maximum power output of the engine and economy thereof through choice of mechanical details, and until recently very little attention has been given to the importance of fuel volume distribution in combustion chambers and its effects upon the performance of the engine. And, where these factors have been considered of importance, no working pattern or bogey has been established by geometrical considerations other than disclosed by my Patent No. 2,138,131, that would give the designers of engines a definite guide in laying out combustion chambers for producing

smoothness in engine operation throughout all sizes of engines, and their compression ratios.

While I have described my invention quite fully and outlined a method for its accomplishment, I desire it to be understood that the invention is not to be limited to the particular illustrative disclosure, and that the scope of my present invention and the rights thereto, I desire to secure are set-forth in the claims hereafter enumerated:

1. In an internal combustion engine including a cylinder block having a plane top face, a cylinder bore extending into the said block from the said face, a piston in the said bore and adapted to be reciprocated therein, and a cylinder head having a plane face for engaging the plane top face of the cylinder block and closing the cylinder bore therein; a combustion chamber extending into the cylinder head from its plane face, and having extending therein a spark plug including a pair of electrodes having their point of ignition within the combustion chamber, the said combustion chamber having concentrically spherical volumes so related to the said ignition point of the electrodes, total combustion volume and total radial distance from said point that the maximum ratio of any increment of combustion volume to the total volume, multiplied by one hundred, and divided by the corresponding ratio of incremental radius to the total radius distance, will come within the limits O, B, C, D, E, G, of the chart shown in Figure 3 of the drawings.

2. In an internal combustion engine including a cylinder block having a plane top face, a cylinder bore extending into the said block from the said face, a piston in the said bore and adapted to be reciprocated therein and a cylinder head having a plane face for engaging the plane top face of the cylinder block and closing the cylinder bore therein; a combustion chamber extending into the cylinder head from its plane face, and having extending therein a spark plug including the electrodes having their ends located within the combustion chamber, the said combustion chamber having concentrically spherical volumes so related to the point of ignition of the said electrodes, total combustion volume and total radial distance from said point, that the maximum ratio of any increment of combustion volume to the total volume, multiplied by one hundred, and divided by the corresponding ratio of incremental radius to the total radius distance, will come within the limits A, B, C, D, E, F, of the chart shown in Figure 3 of the drawings.

3. In an internal combustion engine including a cylinder block having a plane top face, a cylinder bore extending into the said block from the

said face, a piston in the said bore and adapted to be reciprocated therein and a cylinder head having a plane face for engaging the plane top face of the cylinder block and closing the cylinder bore therein; a combustion chamber extending into the cylinder head from its plane face, and having extending therein a spark plug including the electrodes having their ends located within the combustion chamber, the said combustion

10 chamber having concentrically spherical volumes so related to the point of location of the said electrodes, total combustion volume and total radial distance from said space that the maximum ratio of any increment of combustion volume to the total volume, multiplied by one hundred, and divided by the corresponding ratio of incremental radius to the total radius distance, will come within the limits of the area enclosed by the lines A to B, B to C, C to D, D to E, E to F, and F to A, of the bogey shown in Figure 3 of the drawings.

4. In a cylinder head for internal combustion engines, the said cylinder head having a cylinder closing face with a combustion chamber extending into the head from the said cylinder closing face, the said combustion chamber having an ignition point located therein and concentrically spherical volumes so related to the said ignition point, total combustion volume and total radius distance from the said ignition point that the maximum ratio of any radial increment of combustion volume to the total volume, multiplied by one hundred, and divided by the corresponding ratio of incremental radius to the total radius distance, shall come within the vertical limits 150%, 200%, 200%, 140%, 160%, 120%, and 40%, at the corresponding respective horizontal radius distances 10%, 20%, 30%, 34%, 40%, 45%, and 50% from the said ignition point.

5. In an internal combustion engine, a combustion chamber having a combustion chamber having a volume representing the total volume under compression in said engine, a pair of electrodes providing an ignition point representing the ignition point of the said chamber, the said chamber having concentrically spherical portions so related to the point of ignition, total volume, and total radius distance from ignition point, that the maximum ratio of any one-eighth inch 45 radial increment of volume to the total volume, multiplied by one hundred and divided by the corresponding ratio of one-eighth inch incremental radius to the total radius distance, shall come closely within the limits of the area enclosed by the lines extending from A to B, B to C, C to D, D to E, E to F, and F to A of the bogey shown in Figure 3.

IRVING E. ASKE.
